PNEUMATIC MECHANISM FOR HANDLING SHEETS.

Application filed October 7, 1926. Serial No. 140,180.

The main objects of this invention are to provide an improved pneumatic mechanism for handling sheet material; to provide a sheet handling mechanism having an improved 5 vacuum controlled support for the sheets; to provide a sheet support of this kind which is movable to feed the sheets step by step; to provide improved means for breaking the vacuum in a section of said 10 support to permit the removal therefrom of a certain unit of the sheet independently of other units; to provide improved pneumatically controlled means for removing the units from the support; to provide removing 15 means of this kind whereby air under pressure is applied to the section of the support in which the vacuum has been broken for forcing the unit from the support while suction is applied to the opposite face of the 20 unit; to provide improved valve means for controlling the vacuum and pressure in said mechanism; and to provide a sheet handling mechanism of this kind which is particularly adapted for applying tissue patches to 25 pasteboard frames, as in the making of stencils.

An illustrative embodiment of this invention is shown in the accompanying drawings, wherein:

30 Figure 1 is a vertical section of part of a stencil making machine to which this invention is applied.

Fig. 2 is a plan of the same, partly broken away.

35 Fig. 3 is an enlarged detail in section of the suction device which lifts the sheets from the supporting tables.

Fig. 4 is a transverse section, taken on the line 4—4 of Fig. 3.

40 Fig. 5 is an enlarged transverse section, taken on the line 5—5 of Fig. 1, and showing the valve mechanism which controls the vacuum and pressure areas of the sheet supports.

45 Fig. 6 is a horizontal section taken on the line 6—6 of Fig. 5.

Figs. 7, 8, 9 and 10 are enlarged details in section showing the different relative positions of the sheet support and its 50 reciprocating valve.

Fig. 11 is a transverse section, taken on the line 11—11 of Fig. 1.

The improved sheet handling mechanism to which this invention is applied is adapted for use in many different types of machines 55 and for handling various kinds of articles but, as herein illustrated, the invention is applied to a stencil making machine for handling the tissue patches. Inasmuch as this invention relates to the sheet handling 60 mechanism, certain parts of the machine not relating thereto and believed to be unnecessary to a complete understanding of the invention have been omitted from the drawing. 65

In the specific form herein shown, the improved sheet handling mechanism comprises a pair of horizontal tables having foraminous supporting surfaces for the sheets. The tables move step-by-step in one direction for 70 feeding the sheets edgewise to a suitable cutting mechanism, not shown, which cuts each sheet into units or patches of proper size for attachment to the stencil frame. The sheets are held on the tables by vacuum. An improved valve mechanism is arranged to break the vacuum at the area which supports the severed patch independently of the other areas so as to permit the patch to be separated from the table. Air under pressure 75 applied to one face of the patch and supplemented by an improved suction device applied to the opposite face thereof forces the severed patch into engagement with the glued surface of the stencil frame. Improved valve means is provided for rendering the pneumatic mechanism of each table 80 inoperative during the return movement of the table. 85

The movements of the tables are properly 90 timed so that, when one table reaches the limit of its forward movement, the second table will have started forward to supply a patch to the next stencil frame without interrupting the operation of the machine. 95

In the embodiment shown, the improved sheet handling mechanism is applied to a stencil making machine comprising a frame 1 on which is mounted a pair of spaced rails 2 forming a guideway for supporting and 100

guiding stencil frames 3 which are fed through the machine to be operated upon by the various mechanisms.

In the specific form shown, the improved sheet handling mechanism includes a pair of horizontal supporting members or tables 4 adapted to support sheets 5 which are acted upon by an improved pneumatic mechanism including vacuum and pressure means associated with the tables and suction lifting devices 6.

In the construction herein illustrated, two tables of identical construction are used. The tables are arranged in substantially parallel spaced relation and are slidably mounted on rails 7 extending transversely across the frame 1, as shown in Fig. 2.

Each of the tables comprises a bed 8 having a rack 9 on its lower face meshing with gears 10 and 11 which are arranged to move the table step-by-step in one direction for feeding the sheet edgewise toward the stencil blanks 3 and also for returning the table to its initial position. Formed in the top face of the table bed 8, is a plurality of transversely disposed independent pockets 12. Extending longitudinally through the bed 8, is a vacuum chamber 13 which communicates with the pockets 12 through ports 14. Secured to the upper face of the bed 8, is a flat foraminous plate 15 which supports the sheets 5. Orifices 16 in the plate 15 communicate with the pockets 12 and are arranged in areas which are independent of one another and which are of the same contour as the sheet units to be handled. In stencil making machines, where rectangular tissue patches are used, the orifices of the supporting plate are arranged in rectangular form as shown in Fig. 2. The sheet is held on the foraminous plate 15 by the vacuum in the chamber 13 and independent pockets 12.

Extending through the rear end of the vacuum chamber 13 of each table, is a pair of telescoping conduits 17 and 18. The inner conduit 17 projects beyond the outer conduit and serves as the suction conduit for exhausting the air from the vacuum chamber. In order to permit a single patch or other unit of the sheet to be removed from the table independently of the remainder of the sheet, a valve 19 is mounted on the inner end of the tube 17 for breaking the vacuum at the desired area of the supporting surface 15. The outer conduit 18 directs air under pressure to the area in which the vacuum has been broken to force the sheet unit from the supporting plate 15. Also mounted on the inner end of the conduit 17, is a pair of valves 20 and 21 controlling communication between the pockets 12 and a pressure chamber 22.

The valves 19, 20 and 21 and the conduits 17 and 18 reciprocate as a unit and for this

purpose, the conduits are mounted at their rear ends in fittings 23 which are provided with pins 24 slidably mounted in a bearing 25 at the rear of the frame 1. Extending through the fittings 23, is a rod 26 which is supported by a pair of arms 27 pivotally secured to the frame 1 at 28. The rod 26 and fittings 23 are normally urged rearwardly by a spring 29 acting between the rod and the rear end of the frame 1. The rod 26 and fittings 23 are moved against the action of the spring 29 by a cam 30 which coacts with a roller 31 carried by a link 32 secured to the rod 26.

The rearward movement of the fittings 23 is synchronized with the step-by-step movement of the table, so that the valves 19, 20 and 21 move with the table in one direction, when the table advances one step to feed the sheet. During the return stroke of the conduits 17 and 18, the table remains stationary.

Figure 7 illustrates the initial position of the valves. In this position, the entire sheet is subjected to the suction in the pockets 12. When the valve unit advances, the vacuum in the pocket below the end of the sheet is broken and air under pressure is admitted for forcing the patch away from the table.

Connected to each of the fittings 23, and communicating with the conduits 17 and 18 respectively is a suction conduit 33 leading to exhaust means 34 and a pressure conduit 35 leading to an air pump or other suitable source. The conduits 33 and 35 or portions thereof are flexible so as to permit movement of the fittings 23. During the advancing movement of each table, the related conduits 33 and 35 are open and, during the return stroke these conduits are closed by improved valve mechanisms 36 and 37 which are connected together so as to be controlled by a single cam 38 fixed on a driven shaft 39.

In the form shown, Figures 5 and 6, the valve mechanism 36 comprises a block 40 having a chamber 41 communicating with the exhaust means 34. Extending through the block, is a pair of independent passages 42 adapted to communicate with the chamber 41 through ports 43. One of the passages 42 communicates with the suction conduit 33 of one of the tables and the other passage 42 communicates with the conduit 33 of the other table. The ports 43 are controlled by a pair of valves 44 which are arranged so as to open or close communication between the chamber 41 and either one or the other conduit 33. Each of the valves 44 comprises a sliding element 45 having a passage 46 which is shiftable into and out of position to provide communication through the ports 43. The element 45 has a pin 47 which extends into a socket 48 of a bell-crank lever 49 which is pivotally secured to a pin 50 supported in a bracket 51. The sliding elements 45 are yieldingly urged

against the block 40 by springs 52 seated in the sockets 48. Acting between the bell-crank levers 49, is a spring 53 which normally urges the valve elements 45 toward each other. Mounted on the levers 49, are rollers 54 coacting with the cam 38 for shifting the valves 44 against the action of the spring 53.

The valve mechanism 37 comprises a pair 10 of blocks 55 of substantially identical construction, having each a chamber 56 communicating with an air supply conduit 57 and a chamber 58 communicating with the conduit 35 of the related table. Extending 15 through the chambers 56 and 58 is a cylinder 59 having ports 60 and 61 providing communication between the cylinder and the chambers 56 and 58 respectively. Communication between the ports 60 and 61 is controlled 20 by a valve 62 arranged in the cylinder 59. Mounted on the valve 62, is a stem 63, which is connected to the related bell-crank lever 49, whereby the valve 62 is operated in unison with the valve 44. With this improved 25 valve mechanism, during the return stroke of each table 4, the related conduits 33 and 35 are closed while the corresponding conduits of the other table, which is simultaneously advancing step-by-step, are open, so that the related chamber 13 is subjected to suction for holding the sheet 5 and the chamber 22 is subjected to air under pressure for assisting the suction device 6 in removing the 30 end unit or patch. One suction lifting device 35 is used for each table.

In the form shown, each of the suction devices 6 comprises an upright suction tube 64 which is axially shiftable in a bracket 65 mounted on the frame 1. Formed in the tube 64, is a port 66 adapted to register with a passage 67 in the bracket 65 to provide communication between the tube 64 and an exhaust conduit 68. Mounted on the lower end of the tube 64, is a pad or nozzle 69 adapted to engage the end unit of the sheet 5 for lifting it from the table. The tube 64 is located directly above the path of the stencil frames 3 and the nozzle 69 is shaped so as to be able to readily pass through the central opening of the stencil frame during the reciprocation of the suction tube. The tube 64 and nozzle 69 move downwardly to pick up the stencil blank and then move upwardly to deposit the blank on the glued under surface of the stencil frame. When the nozzle occupies its lowermost position, the port 66 registers with the passage 67 to subject the tube 64 to suction. When the nozzle moves upwardly a sufficient distance to deposit the patch on the stencil frame, the port 66 is closed and the tube 64 is restored to atmospheric pressure by the admission of air through ports 70 and 71 formed in the tube 64 and bracket 65 respectively.

65 The upper ends of the tubes 64 are closed

and are rigidly secured to collars 72, which are slidable on pins 73 fixed on a reciprocating member 74. The member 74 is adapted to be continuously reciprocated by a lever 75 pivoted on an arm 76 of the bracket 65. 70 One end of the lever 75 is pivoted to the member 74 and the other end thereof coacts with a rotary cam 77 fixed on a driven shaft 78.

During the forward step-by-step movement of each table, the related suction tube 64 reciprocates with the member 74 for lifting the successive sheet units from the table. During the return stroke of the table, the related tube 64 is automatically disconnected 75 from the reciprocating member 74 and locked in its uppermost position while the other tube 64 is simultaneously connected to the reciprocating member. The means for connecting the tubes 64 with the reciprocating member 74 comprises a pair of latches 79 pivoted to the collars 72 and shiftable into and out of locking engagement with pins 80 on the member 74. The latches 79 are actuated by links 81 connected to cranks 82 fixed on rock shafts 83. The rock shafts 83 are actuated by a cam 84 through the medium of cam rollers 85 mounted on bell-crank levers 86 connected to links 87 which are fastened to cranks 88 of the rock shafts. The cam 84 is preferably mounted on the shaft 39, which also drives the cam 38.

To hold the tube 64 in its uppermost position after the latch 79 has been disengaged from the pin 80, a stop pin 89 is mounted 100 on the bracket 65 in position to engage the lower end of the latch.

In operation, a sheet of tissue is placed on the table 4 when it occupies its initial position of rest at the front side of the machine. The valve mechanism 36 then operates to open communication between the table and the exhaust means and air supply. While the sheet is held on the table by the suction 105 in the chamber 13, the table moves forwardly step-by-step to feed the sheet edgewise to a cutter, not shown, which cuts a unit or patch from the advanced end of the sheet. During each brief period of rest of the table, the valve 19 moves inwardly so as to break the vacuum at the area which supports the severed patch, by cutting off communication between the chamber 13 and the pocket 12 which is directly below the patch. At this 110 time, the nozzle 69 of the suction lifter 6 is in contact with the upper face of the patch.

When the valve unit reaches the position shown in Fig. 8, air under pressure is forced from the chamber 22 into the pocket 12 directly below the severed patch so as to force the edges of the patch away from the supporting surface 15. As the valve unit advances, the nozzle 69 starts upwardly to raise the patch, while the port 14 is momentarily closed by the valve 21. When the 115 120 125 130

valve 21 passes the port 14, air under pressure again passes through the pocket 12 to assist in lifting the patch into engagement with the stencil frame 3. When the nozzle 69 reaches its uppermost position, the tube 64 is restored to atmospheric pressure to release the patch.

When the table 4 reaches the limit of its forward movement, the related suction tube 64 is locked in its uppermost position and the valve mechanism 36 closes the related conduits 33 and 35 so that these parts are inoperative during the return stroke of the table. When one table reaches the limit of its forward movement, the second table starts to advance.

Although but one specific embodiment of this invention has been herein shown and described, it will be understood that numerous details of the construction shown may be altered or omitted without departing from the spirit of this invention as defined by the following claims.

We claim:

1. A device of the class described comprising a member having a foraminous surface for supporting sheets, a vacuum chamber communicating with the orifices of said surface, and a single valve controlling said communication and arranged to break the vacuum at a certain area of said supporting surface independently of other areas communicating with said chamber.

2. A device of the class described comprising a member having a foraminous surface for supporting sheets, the orifices of said surface being arranged in definite areas, a vacuum chamber within said member and communicating with the orifices, and a valve means within said chamber and arranged to break the vacuum at a certain area of said supporting surface independently of other areas.

3. A device of the class described comprising a member having a foraminous surface for supporting sheets, a vacuum chamber adapted to communicate simultaneously with all of the orifices of said surface, said member and chamber being movable to feed the sheets edgewise, and a valve controlling said communication and arranged to break the vacuum at a certain area of said supporting surface independently of other areas communicating with said chamber.

4. A device of the class described comprising a member having a foraminous surface for supporting sheets, a vacuum chamber communicating with the orifices of said surface, said member and chamber being movable in one direction to feed the sheets edgewise, and a valve controlling said communication and arranged to break the vacuum at a certain advanced area of said supporting surface independently of other areas to the rear thereof.

5. A device of the class described comprising a member having a substantially horizontal foraminous surface for supporting sheets, a vacuum chamber located below said surface and communicating with the orifices therein, and a single valve controlling said communication and arranged to break the vacuum at a certain area of said supporting surface independently of other areas communicating with said chamber to permit an individual unit of the sheet to be lifted from said surface independently of other units.

6. A device of the class described comprising a member having a foraminous surface for supporting sheets, a vacuum chamber communicating with the orifices of said surface, valve means controlling said communication and arranged to break the vacuum at a certain area of said supporting surface independently of other areas, and means for applying air under pressure to said certain area.

7. A device of the class described comprising a member having a foraminous surface for supporting sheets, a vacuum chamber communicating with the orifices of said surface, an exhaust conduit communicating with said chamber, a valve adapted to close communication between said exhaust conduit and a certain part of said chamber, and means for applying air under pressure to said certain part.

8. A device of the class described comprising a member having a foraminous surface for supporting sheets, a vacuum chamber adapted to communicate simultaneously with all of the orifices of said surface, an exhaust conduit communicating with said chamber, and a single valve controlling communication between said exhaust conduit and a certain part of said chamber, said valve being also adapted to control communication between said certain part of the chamber and a certain area of said foraminous surface.

9. A device of the class described comprising a member having a foraminous surface for supporting sheets, a vacuum chamber communicating with the orifices of said surface, an exhaust conduit communicating with said chamber, a valve controlling communication between said exhaust conduit and a certain part of said chamber, means for applying air under pressure to said certain part, and an element on said valve arranged to control communication between said certain part of the chamber and a certain area of said foraminous surface.

10. A device of the class described comprising a member having a foraminous surface for supporting sheets, a vacuum chamber adapted to communicate simultaneously with all of the orifices of said surface, a plurality of independent pockets providing communication between said chamber and

- the orifices in independent areas of said surface, and a single valve adapted to control communication between said vacuum chamber and any one of said pockets.

5 11. A device of the class described comprising a member having a foraminous surface for supporting sheets, a vacuum chamber, a plurality of independent pockets providing communication between said chamber and the orifices in independent areas of said surface, an exhaust conduit communicating with said chamber, a valve controlling communication between said exhaust conduit and a certain part of said chamber, 10 means for applying air under pressure to said certain part, and an element on said valve controlling communication between said certain part and one of said pockets.

15 12. A device of the class described comprising a member having a substantially horizontal foraminous surface for supporting sheets, said member being movable step-by-step in one direction for feeding the sheets edgewise, a vacuum chamber within 20 said member below said foraminous surface, said member having a plurality of independent pockets providing communication between said chamber and the orifice in independent areas of said surface, an exhaust conduit communicating with said chamber, a valve controlling communication between said exhaust conduit and a certain part of said chamber, means for applying air under pressure to said certain part, and an 25 element on said valve controlling communication between said certain part and one of said pockets.

30 13. A device of the class described comprising a member having a foraminous surface for supporting sheets, a vacuum chamber communicating with the orifices of said surface, a pair of conduits located in said chamber and arranged one within the other, exhaust means communicating with said chamber through the inner of said conduits, and a valve controlling communication between said inner conduit and a part of said chamber, the outer conduit being adapted to 35 supply air under pressure to said certain part.

40 14. A device of the class described comprising a member having a foraminous surface for supporting sheets, a vacuum chamber communicating with the orifices of said surface, and valve means controlling said communication and arranged to break the vacuum at a certain area of said supporting surface independently of other areas, said member and valve being relatively movable 45 so as to successively position different parts of said chamber in operative relation with said valve.

50 15. A device of the class described comprising a member having a foraminous surface for supporting sheets, a vacuum chamber 55 and a plurality of independent pockets providing communication between said chamber and the orifices in independent areas of said surface, and a valve adapted to control communication between said vacuum chamber and any one of said pockets, said member and valve being relatively movable to place different pockets successively into position to be controlled by said valve.

60 16. A device of the class described comprising a member having a foraminous surface for supporting sheets, a vacuum chamber, a plurality of independent pockets providing communication between said chamber and the orifices in independent areas of said surface, and a valve adapted to control communication between said vacuum chamber and any one of said pockets, said member being movable step-by-step in one direction to feed the sheets edgewise and to bring different pockets successively into position for control by said valve.

65 17. A device of the class described comprising a member having a foraminous surface for supporting sheets, a vacuum chamber, a plurality of independent pockets providing communication between said chamber and the orifices in independent areas of said surface, a valve controlling communication between said chamber and any one of said pockets, and means for applying air under pressure to said one pocket, said member being movable in one direction for feeding the sheets edgewise, said valve being movable in the opposite direction relative to 70 said member for controlling communication between the air supply and said one pocket.

75 18. A device of the class described comprising a member having a foraminous surface for supporting sheets, a vacuum chamber, a plurality of independent pockets providing communication between said chamber and the orifices in independent areas of said surface, a valve controlling communication between said chamber and any one of said pockets, and means for applying air under pressure to said one pocket, said member being movable in one direction for feeding the sheets edgewise, said valve being movable with said member in said one direction and in the opposite direction relative to said member for controlling communication between the air supply and said one pocket.

80 19. A device of the class described comprising a member having a foraminous surface for supporting sheets, a vacuum chamber communicating with the orifices of said surface, valve means controlling said communication and arranged to break the vacuum at a certain area of said supporting surface independently of other areas, means for applying air under pressure to said certain area, and an element on said valve means arranged to control communication between

85 90 95 100 105 110 115 120 125 130

said certain area and the air supply, said member being movable in one direction to feed the sheets edgewise, said valve means being movable with said member in said 5 one direction and movable in the opposite direction for controlling communication between said certain area and the air supply.

20. A device of the class described comprising a member having a foraminous surface for supporting sheets, a vacuum chamber communicating with the orifices of said surface, a pair of conduits located in said chamber and arranged one within the other, the inner of said conduits providing communication between said chamber and exhaust means, and a valve controlling communication between said inner conduit and a certain part of said chamber, the outer conduit being adapted to supply air under 10 pressure to said certain part, said member being movable in one direction to feed the sheets edgewise, said conduits and valve being movable in said one direction with said member and in the opposite direction relative thereto for placing said valve in position to control successively different parts of said chamber.

21. A device of the class described comprising a member having a foraminous surface for supporting sheets, a vacuum chamber communicating with the orifices of said surface, valve means controlling said communication and arranged to break the vacuum at a certain area of said supporting surface independently of other areas, and a suction element outside of said chamber and arranged to separate a unit of the sheet from said certain area.

22. A device of the class described comprising a member having a foraminous surface for supporting sheets, a vacuum chamber communicating with the orifices of said surface, valve means controlling said communication and arranged to break the vacuum at a certain area of said supporting surface independently of other areas, and a suction element outside of said chamber and movable substantially perpendicularly to said foraminous surface for separating a unit of the sheet from said certain area.

23. A device of the class described comprising a member having a foraminous surface for supporting sheets, a vacuum chamber communicating with the orifices of said surface, valve means controlling said communication and arranged to break the vacuum at a certain area of said supporting surface independently of other areas, a nozzle arranged adjacent the outer face of said certain area for separating a unit of the sheet therefrom, a suction conduit communicating with said nozzle, and means for reciprocating said nozzle and conduit.

24. A device of the class described comprising a member having a foraminous sur-

face for supporting sheets, a vacuum chamber communicating with the orifices of said surface, valve means controlling said communication and arranged to break the vacuum at a certain area of said supporting surface independently of other areas, an axially reciprocating suction conduit arranged outside of said chamber substantially perpendicular to said foraminous surface, and a nozzle on the inner end of said conduit for separating a unit of the sheet from said certain area.

25. A device of the class described comprising a member having a substantially horizontal foraminous surface for supporting sheets, a vacuum chamber below said surface and communicating with the orifices of independent areas thereof, valve means controlling said communication and arranged to break the vacuum at a certain area independently of other areas, and a suction element located above said foraminous surface and arranged to separate a unit of the sheet from said certain area.

26. A device of the class described comprising a member having a substantially horizontal foraminous surface for supporting sheets, a vacuum chamber below said surface and communicating with the orifices of independent areas thereof, valve means controlling said communication and arranged to break the vacuum at a certain area independently of other areas, and a vertically reciprocating suction element located above said foraminous surface and arranged to separate a unit of the sheet from said certain area.

27. A device of the class described comprising a member having a substantially horizontal foraminous surface for supporting sheets, a vacuum chamber below said surface and communicating with the orifices of independent areas thereof, valve means controlling said communication and arranged to break the vacuum at a certain area independently of other areas, and a suction element located above said foraminous surface and arranged to separate a unit of the sheet from said certain area, said member being movable step-by-step to feed the sheets edgewise for placing different units thereof successively into operative relation with said suction element.

28. A device of the class described comprising a reciprocating member having a foraminous surface for supporting sheets, a vacuum chamber communicating with the orifices of independent areas of said surface, valve means controlling said communication and arranged to break the vacuum at a certain area independently of other areas, a suction element arranged in position to separate a unit of the sheet from said certain area, exhaust means for said suction element, and means for closing communication between

- said suction element and exhaust means during a certain movement of said member.
29. A device of the class described comprising a reciprocating member having a foraminous surface for supporting sheets, a vacuum chamber communicating with the orifices of independent areas of said surface, valve means controlling said communication and arranged to break the vacuum at a certain area independently of other areas, a suction element arranged in position to separate a unit of the sheet from said certain area, exhaust means for said suction element, said member being movable in one direction to feed the sheets edgewise, and means for closing communication between said suction element and exhaust means during the movement of said member in the opposite direction.
- 20 30. The combination with a support for sheets, of a suction element comprising a nozzle adapted to separate a sheet from the support, a reciprocating member for moving said nozzle toward and away from the support, and a latch adapted to operatively connect said nozzle with said reciprocating member.
31. A device of the class described comprising a member having a foraminous surface for supporting sheets and movable in one direction for feeding the sheets edgewise, a vacuum chamber communicating with the orifices of said surface, means controlling said communication and arranged to break the vacuum at a certain area of said supporting surface independently of other areas, a suction conduit communicating with said vacuum chamber, a pressure conduit communicating with said certain area for supplying air under pressure thereto, and valve

means controlled by the movement of said supporting member for controlling said conduits.

32. A device of the class described comprising a member having a foraminous surface for supporting sheets and movable in one direction for feeding the sheets edgewise, a vacuum chamber communicating with the orifices of said surface, means controlling said communication and arranged to break the vacuum at a certain area of said supporting surface independently of other areas, a suction conduit communicating with said vacuum chamber, a pressure conduit communicating with said certain area for supplying air under pressure thereto, and valve means arranged to close said conduits during the return movement of said supporting member.

33. A device of the class described comprising a member having a foraminous surface for supporting sheets and movable in one direction for feeding the sheets edgewise, a vacuum chamber communicating with the orifices of said surface, means controlling said communication and arranged to break the vacuum at a certain area of said supporting surface independently of other areas, a suction conduit communicating with said vacuum chamber, a pressure conduit communicating with said certain area for supplying air under pressure thereto, a pair of valves adapted to close said conduits during the return movement of said supporting member, and a cam for simultaneously actuating both of said valves.

Signed at Chicago this 20th day of September, 1926.

PAUL A. GOLLNICK.
JOHN J. TOOLAN.
